DESIGN FOR A HAIR WAVING MACHINE

Floyd V. Schleimer, San Francisco, Calif., assignor to Duart Manufacturing Company, Ltd., San Francisco, Calif., a corporation of California

Application August 9, 1937, Serial No. 70,942

Term of patent 7 years

To all whom it may concern:

Be it known that I, Floyd V. Schleimer, a citizen of the United States, and a resident of the city and county of San Francisco, State of California, have invented a new, original, and ornamental Design for a Hair Waving Machine, of which the following is a specification, reference being had to the accompanying drawing forming part thereof.

Referring to the drawing:

Fig. 1 is a side elevational view of a hair waving machine showing my new design.

Fig. 2 is a top plan view of the base taken along the line 2—2 of Fig. 1.

The dominant features of my design as claimed herein reside in the portions shown in full lines.

I claim:

The ornamental design for a hair waving machine, substantially as shown and described.

FLOYD V. SCHLEIMER.
